(57) **CLAIM**

The ornamental design for a hairpiece, as shown and described.

DESCRIPTION

FIG. 1 is a perspective view of a hairpiece showing our new design;

FIG. 2 is a front view thereof;

FIG. 3 is a rear view thereof;

FIG. 4 is a left side view thereof, a right side view being a mirror image of the left side view;

FIG. 5 is a top view thereof;

FIG. 6 is a bottom view thereof; and,

FIG. 7 is a partially enlarged view showing the area 7 in FIG. 2.

The broken lines indicating an enlargement portion of the design form no part of the claimed design.
